(57) **CLAIM**

The ornamental design for a hunting stand with game feeder hanger, as shown and described.

DESCRIPTION

FIG. 1 is a front right perspective view of a hunting stand with game feeder hanger showing my new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top view thereof; and,

FIG. 7 is a bottom view thereof.

The broken lines shown in the figures are for the purpose of illustrating portions of the hunting stand with game feeder hanger and form no part of the claimed design.
